UNITED STATES PATENT OFFICE.

JOSEPH C. SCHWALLER, OF HALBUR, IOWA.

COMBINED TOOL.

SPECIFICATION forming part of Letters Patent No. 372,932, dated November 8, 1887.

Application filed January 31, 1887. Serial No. 225,969. (No model.)

To all whom it may concern:

Be it known that I, JOSEPH C. SCHWALLER, of Halbur, in the county of Carroll and State of Iowa, have invented certain new and useful 5 Improvements in Combined Tools; and I do hereby declare the following to be a full, clear, and exact description of the invention, such as will enable others skilled in the art to which it pertains to make and use it, reference being 10 had to the accompanying drawings, which form part of this specification.

My invention relates to improvements in combined tools; and it consists in, first, the combination of a jaw or handle having a hammer formed upon one end, and having a suitable recess formed through the hammer with a second jaw or handle, which has its shorter end made to extend into the opening in the head, so as to form a means for catching hold 20 of wires, staples, or other similar devices, which are to be drawn out of the wood into which they are driven; second, in the arrangement and combination of parts, as will be more fully described hereinafter, and pointed out 25 in the claims.

The object of my invention is to provide a tool which is especially intended for use in putting up wire fences, and in which a hammer, cutters for cutting the wire, and devices 30 for catching hold of the wire and withdrawing staples, are combined together in a single tool.

Figure 1 is a side elevation of a tool embodying my invention, shown in section. Figs. 2 35 and 3 are edge views of the same. Fig. 4 is a detail view of the cutters, and Fig. 5 is a perspective of one of the jaws.

A represents one of the handles or jaws, which has an ordinary claw-hammer, B, formed 40 upon its end. Through this hammer B is made a suitable opening, C, as shown, in which the shorter end, D, of the other handle, F, operates. The second handle or jaw, F, corresponds in shape so far as its longer end is concerned, and the two jaws are made to separate 45 when left free to move by means of a suitable spring, G.

In order to prevent the jaws from opening when the tool is being used, a suitable link, H, 50 is pivoted to the end of one of the jaws or levers, and which catches over the end of the other handle or lever, so as to lock them

together. The shorter end D of the handle or lever F is provided with a sharp edge, I, upon one side, and which is made to enter a suitable distance into the recess formed by the two projections J upon the hammer B inside of the recesses C. The short end D of this sharp edge I, acting in connection with the sharp edges J, forms a means for catching hold of the ends 60 of wires, staples, and other such devices as are to be either securely held or are to be drawn out of the wood into which they have been driven.

In one edge of the jaw or handle A are 65 formed two suitable recesses, L, and in the edge of the corresponding part of the jaw or handle F is formed a recess, N, which corresponds thereto, the recessed part N coming between two recesses L, as shown. Projecting down through the head, and having its sharp edge to extend into this recess, is a chisel, M, which is held rigidly in position by means of a set-screw, O, which bears against its side, and which chisel is fed forward by means of a 70 set-screw, P. When it is desired to move the chisel forward, the screw O is loosened and the screw P tightened up, and then after the chisel has been given the desired adjustment the screw O is tightened into position again. In 75 the side of the jaw F is made a suitable recess. In this recess a reversible blade or cutter, Q, is placed, which can have its cutting-edge reversed whenever the edge in connection with the chisel M becomes dull. The cutting-edge 80 of this blade Q does not pass the edge of this chisel so as to produce a shearing action, but it advances toward the chisel to within any desired distance for the purpose of cutting the wires. In the opposite side of the jaw A there 85 are made two other recesses, R, which are preferably made circular in shape, so as to be adapted to receive wires, and the jaw F has a recess, S, which corresponds with the recesses R. When the two jaws are closed, the recess 90 in the jaw F moves so as to grasp the wire or other similar object, and thus hold it securely.

It will be seen from the above that when the jaws are fastened together by the clasp H the claw of the hammer is adapted for pulling 100 nails and staples, and the hammer portion for driving nails, staples, and other such objects, the cutters to cut the wires, the short end D of the jaw F to catch hold of staples, the ends

of wires, and other such objects, and the recesses R S to catch hold of the long wire, for the purpose of exerting a pull upon it. All the tools which are used in the making of wire fences are here combined in a single tool, thereby saving the operator the time and trouble in changing from one tool to another when at work.

Having thus described my invention, I ¹⁰ claim—

1. In a combined tool, the combination of the handle A, having a hammer and claw formed upon one end and a recess formed through the hammer, and provided with a chisel, M, ¹⁵ with the handle F, pivoted upon the one A, and having a short end, D, which extends up into the recess and is provided with a sharp edge, I, to operate in connection with the edges J, formed upon the hammer, and the blade Q, ²⁰ which is inserted in the handle and adapted

to operate in connection with the chisel, substantially as shown.

2. In a combined tool, the combination of a handle, A, having a hammer and claw formed upon one end, and a recess formed through the hammer, with the handle F, pivoted upon the one A, and having a short end, D, which extends up into the recess, and which is provided with the sharp edge I, and which operates in connection with the edges J, formed upon the ³⁰ hammer, the inner side of the hammer and the projection D serving to catch hold of articles, substantially as described.

In testimony whereof I affix my signature in presence of two witnesses.

JOSEPH C. SCHWALLER.
